SUPPORT CLIP FOR CLOTHES HANGERS

Howard A. Eklind, 2627 N. Western Ave., Chicago, Ill.

Filed Apr. 19, 1963, Ser. No. 74,519

Term of patent 14 years

(Cl. D80—8)

FIG. 1

FIG. 4

FIG. 1 is a perspective view of a support clip for clothes hangers embodying my new design; and

FIGS. 2, 3 and 4, respectively, are front, end and top views thereof.

I claim:

The ornamental design for a support clip for clothes hangers, as shown.
